ABSTRACT

A current mirror circuit exhibits improved current matching by applying a switching signal to ground path switches in series with transistors in both a reference path and an output path of the current mirror. The switching signal may comprise a high-frequency signal, which may be phase modulated. A plurality of matched, parallel-connected output transistors may be selectively enabled by qualifying the switching signal applied to each corresponding series-connected ground path switches by decoded digital modulation data. In one embodiment, the modulation data is decoded to thermometer-coded representation. In one embodiment, the switching signal path is identical to the reference and output circuits.

SWITCHED CURRENT MIRROR WITH GOOD MATCHING

PRIORITY CLAIM

This application claims priority to U.S. Provisional Patent Application Ser. No. 61/388,326, titled "Switched Current Mirror with Good Matching," filed Sep. 30, 2010, the disclosure of which is incorporated herein by reference in its entirety.

BACKGROUND

A current mirror is a well-known circuit designed to copy a current through one active device (such as a transistor) by controlling the current in another active device, keeping the output current constant regardless of loading. The output current may be applied to a different node than the input current, and has a current ratio (with respect to the reference current) set by the ratio of input and output transistors used.

The transistor size ratio, and hence the current ratio, may be altered by connecting a plurality of output transistors in parallel. By adding switches in series with the parallel-connected output transistors, the number of output transistors active in the current mirror at any given moment can be changed by controlling the switches, and in this manner the current ratio can be dynamically controlled. When the switches are controlled by digital signals, the analog output current can be digitally controlled, acting like a Digital to Analog Converter (DAC).

FIG. 1 depicts a current mirror in which the active devices are NMOS transistors M_1 and M_2 . Due to R_1 , current I_1 flows through the reference transistor M_1 , causing a gate-source voltage V_{gs1} . The gate-source voltage V_{gs2} for output NMOS transistor M_2 is the same ($V_{gs1}=V_{gs2}$), resulting in current I_2 when the transistor M_4 , acting as a switch, is in a conducting state. This occurs when the switch S_1 is in the upper position, placing a high voltage on the gate of M_4 . Transistor M_3 in series with reference transistor M_1 also acts as a switch, which is always "on," as its gate terminal is tied high. When switch S_1 is in the lower position, switch M_4 is non-conducting, or open, causing current I_2 to go to zero. Accordingly, the switch S_1 controls current I_2 to be either proportional to I_1 or zero.

Currents I_1 and I_2 are nearly equal when the reference transistor M_1 and output transistor M_2 have equal layout, and switching transistors M_3 and M_4 are also the same (indeed, M_3 exists only for such path matching, as it is always in an "on" state), and of course $R_1=R_2$. In this case, if S_1 switches to apply a pulse train on the gate of M_4 having a 50% duty cycle, the current ratio I_2/I_1 is one half ($\frac{1}{2}$). Both the frequency and the pulse-width of the switching signal applied to the gate of M_4 will influence this current ratio. Switching speed and pulse-width are influenced by product junction temperature and by production process spread, which cause an unacceptably large spread on the output current I_2 . Some of this spread can be compensated by a feedback system. However, measuring a high-frequency switching signal has limited accuracy, limiting the performance of such a feedback system.

SUMMARY

A current mirror circuit exhibits improved current matching by applying a switching signal to ground path switches in series with transistors in both a reference circuit and an output circuit of the current mirror. The switching signal may comprise a high-frequency signal, such as a Radio Frequency

(RF) carrier, which may be phase modulated. A plurality of matched, parallel-connected output transistors may be selectively enabled by qualifying the switching signal applied to each corresponding series-connected ground path switch by decoded digital modulation data. In one embodiment, the modulation data is decoded to thermometer-coded representation. In one embodiment, the switching signal path is substantially identical to the reference and output circuits.

One embodiment relates to a high-frequency, modulating current mirror circuit. The circuit includes a reference transistor diode-connected between an output power controller and a switched path to signal ground. The circuit further includes a plurality of output transistors connected in parallel between a common load and independent switched paths to signal ground, wherein the gates of the output transistors are all connected to the gate of the reference transistor. The circuit also includes a high-frequency input operative to receive a high-frequency signal, and a digital decoder operative to receive and decode a digital modulation code. A plurality of logic functions are associated with the plurality of output transistors. Each logic function is operative to receive the high-frequency signal and a bit of the decoded modulation code. The output of each logic function is operative to control the respective ground path switch of an output transistor.

Another embodiment relates to a method of modulating a high-frequency signal in a current mirror circuit. A current through a diode-connected reference transistor is controlled by selectively coupling the transistor to signal ground via a switch controlled by a high-frequency signal. The current through some of a plurality of output transistors connected in parallel and having a common load is selectively controlled by selectively coupling some of the transistors to signal ground via respective switches controlled by the high-frequency signal and a digital modulation code, wherein the gates of the output transistors are all connected to the gate of the reference transistor.

BRIEF DESCRIPTION OF THE DRAWINGS

FIG. 1 is a schematic diagram of a prior art current mirror circuit.

FIG. 2 is a functional schematic diagram of a current mirror circuit according to one embodiment of the present invention.

FIG. 3 is a functional schematic diagram of a current mirror circuit having a plurality of output transistor cells, according to one embodiment of the present invention.

FIG. 4 is a functional schematic diagram of a current mirror circuit having a plurality of output transistor cells and improved matching, according to one embodiment of the present invention.

FIG. 5 is a flow diagram of a method of modulating a high-frequency signal in a current mirror circuit, according to one embodiment of the present invention.

DETAILED DESCRIPTION

FIG. 2 depicts an improved current mirror circuit 10, in which the transistor notation from the prior art circuit of FIG. 1 is retained for clarity of explanation. Note that while the transistors depicted are NMOSFETs, this is not a limitation of the present invention, and other transistor types may be utilized. The current mirror circuit 10 is configured as a Radio Frequency (RF) amplifier. The output power is controlled by a linear power control circuit 12 in the reference circuit, controlling the current I_1 through diode-connected reference transistor M_1 and an associated, series-connected ground path switch M_3 . As known in the art, a diode-connected transistor

is a transistor having a short circuit between the gate and drain nodes. As in the prior art, the gate connection of output transistor M_2 to reference transistor M_1 causes a gate-source voltage equality ($V_{gs1}=V_{gs2}$), resulting in a proportional current I_2 flowing through the output transistor M_2 and its series-connected ground path switch M_4 . An inductive load **14** drives an output signal to an antenna **16**.

In the current mirror circuit **10**, both ground path switches M_3 and M_4 are controlled by a signal generated from switching control function **18**. In general, the switching signal is a high-frequency signal (e.g., RF) with limited rise/fall times and unknown duty cycle, due to variations in temperature, processing, and the like. By applying the switching signal to both the reference circuit ground path switch M_3 and the output circuit ground path switch M_4 , matching between the reference current I_1 and output current I_2 is maintained, as variations in the switching signal are applied equally to both sides of the current mirror. When M_2 and M_4 are matched to M_1 and M_3 , respectively, and the same switching signal is applied to M_3 and M_4 , then $I_2=I_1$.

In the circuit of FIG. 2, the output current I_2 , and hence the current ratio I_2/I_1 , can be scaled by altering the effective size of output transistor M_2 relative to reference transistor M_1 —such as by connecting two or more output transistors in parallel. By independently switching the parallel output transistors M_2 in and out of the circuit, the current ratio I_2/I_1 can be dynamically controlled. This requires a separate ground path switch M_4 for each parallel-connected output transistor M_2 . Aside from the ability to independently enable the output transistors M_2 —that is, even for a fixed current ratio configuration—each output transistor M_2 should be connected in series with a ground path switch M_4 , as the series resistance of switches M_3 and M_4 influence the mirror matching.

In one embodiment utilizing parallel output transistors, the RF amplifier of FIG. 2 implements a polar modulator, suitable for use in e.g. a Bluetooth® transmitter. In this embodiment, the output circuit **20**, comprising an output transistor M_2 and series-connected ground path switch M_4 , may be replicated and connected in parallel, with the transistors being selectively switched in and out of the output circuit **20** to dynamically vary the current ratio I_2/I_1 . In particular, phase information is modulated onto a 2.45 GHz carrier signal, represented by the RF input to the switching control function **18**. This RF signal is used to control the switching of all ground path switches M_3 , M_4 . A binary Amplitude Modulation (AM) code, also input to the switching control function **18**, is decoded and separate bits applied to the parallel output ground path switches M_4 , along with the phase-modulated RF carrier.

This amplifier circuit is depicted in greater detail in FIG. 3. A linear power control circuit **12** in the reference circuit **19** controls the output power of the signal applied to the load **14** and antenna **16**, by controlling the voltage applied to a diode-connected reference transistor M_1 . This determines the current I_1 in the reference circuit **19**, which is mirrored by currents summing to I_2 in the output circuit **20**. The output circuit **20** of the current mirror comprises a plurality of parallel-connected output cells **22** (in one embodiment, 255 output cells **22**). Each output cell **22** includes an output transistor M_2 gate-connected to the reference transistor M_1 , a series-connected ground path transistor M_4 configured to function as a switch, and a logic function **24** applying a switching signal to the ground path switch M_4 .

The output cells **22** are component-matched to each other. Additionally, the output transistor M_2 and ground path switching transistor M_4 are matched to the reference transistor M_1 and ground path switching transistor M_3 , respectively.

As used herein, component-matched means that the physical size of active features, wire lengths, layout, environment, and the like, of the cells implemented in an integrated circuit (IC) are as closely matched as possible. One known method of component matching is to create a representative circuit, such as an output cell **22**, in a library, and “instantiate” or create multiple instances of the same library cell on an IC chip, to create the plurality of actual, component-matched cells **22**.

A decoder **26** receives binary AM data, such as in 8-bit bytes. The decoder decodes the 8-bit AM data into, e.g., 255 thermometer-coded bits. One such bit is applied to the logic function **24** of each corresponding output cell **22**. A phase-modulated RF carrier signal is applied to the other input of the logic function **24**. In one embodiment (e.g., where the decoder **26** output is positive logic), each logic function **24** implements a logical AND between the respective decoded AM bit and the RF carrier signal. In this case, the RF carrier signal is applied to the gate of the ground path switching transistor M_4 in each output cell **22** when the corresponding decoded AM bit is a logical one. The RF carrier signal is also applied to the gate of the ground path switching transistor M_3 in the reference circuit **19**. Thus, for each output cell **22** having a corresponding “enabled” decoded AM bit, the current in the cell **22** matches that through the reference transistor M_1 . Because the output cells **22** are connected in parallel, these currents sum at the output **14**. For each output cell **22** for which the corresponding decoded AM bit is a logical zero, the ground path switch M_4 is open, and no current flows in the cell **22**. Thus, the output current applied to the load **14** has an amplitude determined by the digital AM modulation code. In particular, the output current is an integral multiple of the reference current, the multiplier being the number of enabled output cells **22**.

Note that the provision of 255 output cells **22**, and decoding the 8-bit AM data into a thermometer-coded representation, provides the greatest granularity of control, as amplitude of the sum output current I_2 may assume any of 255 values. However, this is not a limiting feature of the present invention. In other embodiments, a different digital coding or a combination of codes (e.g., a combination of binary and thermometer codes) may be utilized. This may reduce silicon area of the current mirror circuit by providing fewer than 255 output cells **22**, with some loss of granularity of control of the output current I_2 amplitude.

FIG. 4 depicts a current mirror amplifier circuit having even greater matching, and hence more stable and predictable output current I_2 . In this embodiment, the reference circuit **19** uses the same component-matched cell **22** as the parallel-connected output circuit **20**. That is, the reference transistor M_1 and series-connected ground path switching transistor M_3 are not only closely matched to output transistors M_2 and ground path switching transistors M_4 , respectively, but they are substantially identical. For example, the cells **22** are preferably instantiations of the same layout cell from a library. Additionally, the cell **22**, and hence the reference circuit **19**, includes the logic function **24**. To enable the reference circuit **19** at all times, one input of the logic function **24** is tied to a static enabling value, such as a logical one in the case of an AND gate. This ensures that the RF switching signal applied to the gate of the reference ground path switching transistor M_3 exactly matches that applied to the ground path switching transistor M_4 of each enabled output cell **22** (e.g., substantially identical propagation delay, fan-out, drive strength, capacitive loading, and the like).

FIG. 5 depicts a method **100** of modulating a high-frequency signal in a current mirror circuit. A high-frequency signal is received (block **102**), such as a phase-modulated RF

carrier signal. The high-frequency signal is applied to a ground path switch, such as a transistor configured to function as a switch, in series with a reference transistor, to control the current through the reference transistor (block 104). Digital modulation data, such as amplitude modulation data, is received and decoded, such as into thermometer-coded form (block 106). A plurality of output transistors, connected in parallel and each gate-connected to the reference transistor, are selectively enabled by applying a logical function, such as an AND, of the high-frequency signal and the decoded modulation data, to ground path switches, such as transistors configured to function as switches, in series with each output transistor, to control the current through the output transistors (block 108). The currents of the enabled output transistors, each of which is proportional to the current through the reference transistor, are then summed to form a modulated output current.

Current mirror circuits as disclosed herein exhibit superior current matching as compared to prior art current mirrors, without requiring any feedback mechanism. By switching both reference and output circuits of a current mirror with the same or closely related switching signals, variations in the switching signals, such as limited rise/fall times and unknown duty cycle, do not deleteriously affect current matching, as the same effects are realized in each side of the current mirror. By closely matching output cells with each other and with a reference circuit, and selectively enabling output cells via decoded modulation data, embodiments of the present invention realize a modulating amplifier having predictable, stable performance and efficient operation.

Those of skill in the art will readily realize that numerous variations on the inventive concepts taught herein are readily possible, and fall within the scope of the appended claims. For example, the logic function 24 may be implemented by any logic, including AND, NAND, OR, NOR, XOR, or XNOR functions, or combinations thereof, as required or desired, with corresponding logic levels generated by the decoder 26. Furthermore, the decoder 26 may decode modulation data to a representation other than thermometer-coded values. Additionally, while representative circuits herein have utility as amplifiers, it is clear from the disclosure that the same inventive principles could be applied to realize other circuit functionality, such as simple Digital to Analog Conversion (DAC). In general, the present invention may be carried out in other ways than those specifically set forth herein without departing from essential characteristics of the invention. The present embodiments are to be considered in all respects as illustrative and not restrictive, and all changes coming within the meaning and equivalency range of the appended claims are intended to be embraced therein.

What is claimed is:

1. A high-frequency, modulating current mirror circuit, comprising:
  - a reference transistor diode-connected between an output power controller and a switched path to signal ground;
  - a plurality of output transistors connected in parallel between a common load and independent switched paths to signal ground, the gates of the output transistors all connected to the gate of the reference transistor;
  - a high-frequency input operative to receive a high-frequency signal;
  - a digital decoder operative to receive and decode a digital modulation code; and
  - a plurality of logic functions corresponding to the plurality of output transistors, each logic function operative to

receive the high-frequency signal and a bit of the decoded modulation code, the output of each logic function operative to control the respective ground path switch of an output transistor.

2. The circuit of claim 1 wherein the reference transistor and ground path switch, and each of the plurality of output transistors and ground path switches, are formed as component-matched cells.
3. The circuit of claim 1 wherein each logic function implements a logical AND function.
4. The circuit of claim 1 wherein the high-frequency signal comprises a radio frequency (RF) carrier signal.
5. The circuit of claim 4 wherein the RF carrier signal is phase-modulated.
6. The circuit of claim 1 wherein the digital modulation code comprises amplitude modulation data.
7. The circuit of claim 6 wherein the current mirror circuit implements a polar modulator.
8. The circuit of claim 1 wherein the high-frequency signal is operative to directly control the ground path switch of the reference transistor.
9. The circuit of claim 1 further comprising an additional logic function, implementing the same logic as the plurality of logic functions, operative to receive the high-frequency signal and a static enabling value, the output of the additional logic function operative to control the ground path switch of the reference transistor.
10. The circuit of claim 9 wherein the component-matched cells further include the respective logic functions.
11. The circuit of claim 1 wherein the decoded modulation code is a thermometer code.
12. A method of modulating a high-frequency signal in a current mirror circuit, comprising:
  - controlling a current through a diode-connected reference transistor by selectively coupling the transistor to signal ground via a switch controlled by a high-frequency signal; and
  - selectively controlling the current through one or more of a plurality of output transistors connected in parallel and having a common load by selectively coupling one or more of the transistors to signal ground via respective switches controlled by the high-frequency signal and a digital modulation code, wherein the gates of the output transistors are all connected to the gate of the reference transistor.
13. The method of claim 12 wherein the reference transistor, the output transistors, and their respective ground path switches are formed as component-matched cells.
14. The method of claim 12 wherein selectively controlling the current through some of the output transistors comprises directly controlling the ground path switches with the output of a logical operation applied on the high-frequency signal and digital modulation code.
15. The method of claim 14 wherein the logical operation is a logical AND function.
16. The method of claim 12 further comprising receiving digital modulation data and decoding the data to generate a digital modulation code.
17. The method of claim 16 wherein the digital modulation code is a thermometer code.
18. The method of claim 12 wherein controlling a current through a diode-connected reference transistor by selectively coupling the transistor to signal ground via a switch controlled by a high-frequency signal comprises directly controlling the ground path switch with the high-frequency signal.
19. The method of claim 12 wherein controlling a current through a diode-connected reference transistor by selectively

coupling the transistor to signal ground via a switch controlled by a high-frequency signal comprises controlling the ground path switch with the output of the logical operation applied on the high-frequency signal and a static enabling signal.

20. The method of claim **19** wherein the logical operation is a logical AND function and the static enabling signal is a logical “1”.

21. The method of claim **19** wherein the component-matched cells further include circuits implementing the logical operation.

22. The method of claim **12** wherein the high-frequency signal is a phase modulated radio frequency (RF) signal.
